DESIGN FOR A BUTTON TRIMMING FOR WEARING APPAREL

Sidney Baritz, Great Neck, N. Y.

Application May 3, 1939, Serial No. 84,761

Term of patent 14 years

To all whom it may concern:

Be it known that I, Sidney Baritz, a citizen of the United States and a resident of the town of Great Neck, in the county of Nassau and State of New York, have invented a new, original, and ornamental Design for a Button Trimming for Wearing Apparel, of which the following is a specification, reference being had to the accompanying drawing, forming a part thereof.

Fig. 1 is a top elevational view of my button trimming for wearing apparel showing my new design.

Fig. 2 is a bottom elevational view of my button trimming for wearing apparel shown in Fig. 1.

Fig. 3 is a side elevational view of my button trimming for wearing apparel shown in Figs. 1 and 2.

I claim:

The ornamental design for a button trimming for wearing apparel, substantially as shown.

SIDNEY BARITZ.
